UNITED STATES PATENT OFFICE.

OLIN H. BASQUIN, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,324, dated July 13, 1897.

Application filed June 15, 1897. Serial No. 640,920. Term of patent 14 years.

To all whom it may concern:

Be it known that I, OLIN H. BASQUIN, a citizen of the United States, residing at Chicago, in the county of Cook, State of Illinois, have 5 invented and produced a certain new and useful Design for Prism-Lights, of which the following is a description.

My invention relates to a new design for prism-lights and is illustrated in the accompanying drawings, wherein—

Figure 1 is a perspective view of a prism-light embodying my design. Fig. 2 is a sectional view of the prism-light shown in Fig. 1.

As illustrated in the drawings, the prism-light A is provided on one face with the pro-

jecting prisms B B and on the other face with the corrugations or projecting curved parts C C, such parts shown as having certain dimensions and angles; but the essential feature of my design is the prism-light having prisms projecting from one side and the curved parts C C projecting from the other side thereof.

I claim—

The design for a prism-light as herein shown and described.

OLIN H. BASQUIN.
